R. T. ALLAN

MAIL BOX SIGNAL ATTACHMENT

Filed March 25, 1924

Inventor.

R. T. Allan

By *Clarissa A. O'Brien*
Attorney

UNITED STATES PATENT OFFICE.

ROLLO THOMAS ALLAN, OF WEST HOMESTEAD, PENNSYLVANIA.

MAIL-BOX-SIGNAL ATTACHMENT.

Application filed March 25, 1924. Serial No. 701,808.

To all whom it may concern:

Be it known that I, ROLLO THOMAS ALLAN, a citizen of the United States, residing at West Homestead, in the county of Allegheny 5 and State of Pennsylvania, have invented certain new and useful Improvements in a Mail-Box-Signal Attachment, of which the following is a specification.

This invention relates to new and useful 10 improvements in mail boxes or receptacles where the same are used in connection with rural delivery and has for its principal object to provide a signal attachment whereby a person may readily ascertain whether or 15 not there is mail in the box.

A further object of the invention is to provide a signal attachment of the above mentioned character, which is adapted to be operated simultaneously with the opening of 20 the closure whereby the mail may be deposited in the box, the signal being adapted to be manually returned to its non-indicating position after a person has removed the mail from the mail box.

25 A still further object of the invention is to provide a device of the above mentioned character, which is simple in construction, inexpensive, strong and durable and furthermore adapted for the purposes for which it 30 is designated.

Other objects and advantages of this invention will become apparent during the course of the following description.

In the accompanying drawing forming a 35 part of the specification and in which like numerals designate like parts throughout the same,

Figure 1 is a front elevation of a mail box with my signal attachment in position thereon, parts being broken away,

40 Figure 2 is a side elevation thereof with the signal member in an inoperative position, and

Figure 3 is a similar view showing the 45 signal member in an indicating or operative position.

In the drawing wherein for the purpose of illustration is shown the preferred embodiment of my invention, the numeral 1 designates generally a mail box which is of the 50 well known construction and is provided with the hinged cover 2. Ordinarily with the mail boxes now in use in connection with the rural free delivery of the mail, a person 55 does not know whether or not mail has been

deposited in his box by the letter carrier and consequently must spend considerable time in going to the mail box to ascertain whether or not there has been deposited in the mail box mail. For the purpose of preventing the loss of unnecessary time, I have provided an attachment whereby when mail is deposited in the box by the letter carrier or by the person for collection by the letter carrier, a signal will be given to indicate 60 that mail is in the box, thus saving both the mail carrier and the person owning the box a great deal of time.

65 My signal attachment comprises the provision of a crank lever 3 which extends 70 through the side of the box adjacent the bottom thereof in the manner clearly shown in the drawing. The outer end of the crank lever 3 is provided with the upstanding portion 4 and the latter carries thereon the signal flag 5. The upstanding portion 4 and the flag carried thereby normally extends adjacent and parallel with the side of the mail box in the manner clearly illustrated 75 in Figure 1 of the drawing. The inner end 80 of the crank lever 3 is adapted to be engaged with the actuating means to be presently described.

85 The actuating means for the signal comprises an elongated rod or lever 7, the upper end of which is pivotally connected to the hinged cover 2 in the manner clearly illustrated at 8 in the drawing and is supported preferably adjacent the side of the mail box in which the crank lever is supported. The lower end of the elongated rod 90 7 is provided with the longitudinally extending slot 9 and which normally engages the inner end of the crank lever 3.

95 When the parts are arranged as shown in Figure 2 of the drawing, the signal member is supported in an inoperative position and thus indicates that there is no mail in the box. When a mail carrier deposits mail in the box, the hinged cover 2 is raised so that the mail may be deposited therein and upon the raising of the cover 2, the rod 7 being connected at its upper end thereto and the lower end of the rod being in engagement 100 with the inner end of the crank lever 3, will cause the crank lever 3 to rotate so that the signal flag 5 will be swung outwardly to the position shown in Figure 3 of the drawing, whereby the same will extend beyond 105 the front face of the mail box and thus indicate 110

cate that there is mail in the receptacle. To limit the outward movement of the signal flag 5, I provide a stop pin on the side of the mail box for engagement with the up-
5 standing portion 4, in the manner clearly illustrated in Figure 3.

After mail has been deposited in the box, the hinge cover 2 is turned to its normal position and the downward movement of the elongated rod 7 in the mail box 1 will not interfere with the operation of the signal member 5 which has been extended. The slot 9 permitting the rod 7 to return to its normal position without causing the rolling movement of the crank lever 3. After the mail has been removed from the receptacle, the signal flag is returned to its normal position by the person removing the mail by pushing the flag supporting arm 4
10 inwardly to the position shown in Figure 2 of the drawing. This operation permits the crank lever to return to its normal position whereby the raising of the cover or closure 2 will again cause the flag to be moved outwardly to an indicating position.

It will thus be seen from the foregoing description, that a mail box signal attachment has been provided for use in connection with rural delivery whereby considerable time will be saved both by the letter carrier and by the person owning the box and will prevent the unnecessary trips to the mail box in order to ascertain whether or not mail is deposited therein. The parts are so arranged as not to interfere with the operation of the opening or closing of the hinge cover and furthermore will not interfere with the depositing of the mail or the removal of the same from the box. The
30 material from which my improved signal attachment is constructed, may be of any
35

suitable character, and I do not wish to limit myself to the particular kind of material to be used.

A mail box signal of the above mentioned 45 character will at all times be positive in its operation and furthermore will not require the material changing of the construction in the mail box in order to place the signal attachment in position thereon. A 50 device of this character may be manufactured at a very low cost and will further be strong and durable.

While I have shown the preferred embodiment of my invention, it is to be understood that various changes in the size, shape and arrangement of parts may be resorted to without departing from the spirit of the invention and the scope of the appended 55 claim.

Having thus described the invention, what I claim is:—

In combination with a mail box having a hinged cover, a visual signal associated therewith comprising a crank lever extending through the side of the box adjacent the bottom thereof, the outer end of said lever having an upstanding portion provided with a signal member thereon, an elongated rod disposed in said box adjacent the aforementioned sign and pivotally connected at its upper end to said cover, the lower end of said rod having an elongated slot provided therein for engagement with the inner end of the crank lever, said crank lever adapted to swing the upstanding portion and flag member carried thereon outwardly to an indicating position upon the opening 70 of said cover.

In testimony whereof I affix my signature.

ROLLO THOMAS ALLAN.
